UNITED STATES PATENT OFFICE

131,834

DESIGN FOR AN ARM BAND

Sven E. Meland, Evanston, Ill.

Application January 5, 1942, Serial No. 105,019

Term of patent 7 years

To all whom it may concern:

Be it known that I, Sven E. Meland, a citizen of the United States, residing at Evanston, in the county of Cook and State of Illinois, have invented a new, original, and ornamental Design for Arm Bands, of which the following is a specification, reference being had to the accompanying drawing, forming part thereof, in which—

Fig. 1 is an outside face view of an arm band showing my new design;

Fig. 2 is an edge view of the band.

I claim:

The ornamental design for an arm band, as shown.

SVEN E. MELAND.
